INTERNAL COMBUSTION ENGINE

Vernon D. Brott, Franklin Park, Ill.

Application May 23, 1933, Serial No. 672,520

4 Claims. (Cl. 123—50)

The invention relates to improvements in internal combustion engines and has for its primary object the provision of an internal combustion engine of simple construction and highly efficient in use.

Another object of the invention is the provision of an improved internal combustion engine equipped with an improved control valve arrangement which is highly efficient in use.

Another object of the invention is the provision of an improved internal combustion engine provided with improved means for supplying fuel thereto.

Other objects will appear hereinafter.

The invention consists in the combinations and arrangements of parts hereinafter described and claimed.

The invention will be best understood by reference to the accompanying drawings, forming a part of this specification, and in which

Fig. 1 is a partial top plan view of an internal combustion engine embodying the invention;

Fig. 2, a partial vertical longitudinal section taken substantially on line 2—2 of Fig. 1;

Fig. 3, a partial horizontal section taken substantially on line 3—3 of Fig. 2;

Fig. 4, a partial horizontal section taken substantially on line 4—4 of Fig. 2;

Fig. 5, an enlarged vertical section of the control valve of the engine, and

Fig. 6, a view similar to Fig. 5, but showing the parts in different operative positions.

The embodiment of the invention illustrated in drawings comprises suitable end casings 10, oil splash pan 11 and an intermediate casing 12 divided by transverse double partitions 13 into a plurality of cylinder chambers 14, as indicated.

At intervals, see Fig. 3, the sides of casing 12 are oppositely indented to form segmental guides 15, adapted and arranged to contact with and guide the opposite sides of reciprocating cylinders 16—said guides being relieved as shown, to permit oil or other cooling liquid to flow freely between portions of said cylinders and guides.

Each of the cylinders 16 is provided with lateral-projections or bosses 17 projecting laterally through slots between the guides 15 and thus serving to further guide the corresponding cylinder 16 in its reciprocations. Suitable oil holes 18 are provided in the projections 17 and suitable connecting rods 19 are connected, as shown, with the projections 17 and with cranks 20 of the engine crank-shaft. A piston 21 operates in each of the cylinders 16 and is connected by a suitable connecting rod 22 with a corresponding

crank 23 on the crank-shaft 24. Crank-shaft 24 is mounted in suitable bearings 25 in the casing of the engine as indicated. By this arrangement it will be observed that during the normal operation of the engine both the cylinders 16 and the pistons 21 will reciprocate relatively to each other and to the enclosing casing.

Each cylinder 16 reciprocates on a pipe or tube 26 sliding freely through a stuffing box 27 in the head of the cylinder, said stuffing box being provided with an oil well 28 for lubricating purposes. These stuffing boxes 27 contain alternating split piston rings and recessed collars, with the rings seated in the recesses of said collars. Said piston rings are constructed to act in contraction on the pipes 26, and are slightly thinner than the depth of the recesses in which they are confined, whereby there will be slight clearances between the faces of said rings and the opposed surfaces of said recessed collars, thus permitting said rings to expand and contract without frictional resistance.

Each pipe 26 communicates at its top with an enlarged pipe 29 having individual intake and exhaust passages 30 and 31 therein, as shown. The enlarged pipe sections 29 are formed integral with a cylindrical valve casing 32 mounted on top of the casings 10 and 12 and containing a rotatable tubular cylindrical valve member 33 provided on its periphery with suitable packing rings on opposite sides of the intake and exhaust ports, as shown. These packing rings are held stationary by set screws as shown to minimize friction and wear.

Arranged within and traversing the rotary valve 33 are exhaust conduits 34 arranged to place the exhaust passages 31 in periodical and proper communication with the exhaust ports 35 formed in the casing 32, as shown. Likewise the valve 32 is also provided with conduits 36 traversing the same and periodically placing the intake passages 30 in communication with the intake ports 37 formed in the walls of the casing 32. The arrangement is such that, as the valve 33 rotates, the intake and exhaust passages 30 and 31 will be properly and periodically placed in communication with the intake and exhaust ports of the engine and thereby suitable fuel charges supplied to and exhausted from the cylinder 16, as will be readily understood by those skilled in this art. It is to be noted that the intake of the fuel charges thus occurs when the cylinder head and piston are substantially at their position of closest approach so that the incoming charge is admitted at sub-

stantially the center of the combustion space therein and is expanded therein in both directions during the normal intake operations and is then compressed from both directions so that a superior mixture of the fuel charge is formed at the time of ignition, thus materially increasing the efficiency of the operation of the engine.

The valve 33 is constantly rotated by means of a sprocket wheel 38 connected by chain-belt 39 with a smaller sprocket wheel 40 on the crank-shaft 24, said valve being thus connected to rotate at one-half the speed of the crank-shaft to properly time the opening and closing of the intake and exhaust ports, as will be readily understood by those skilled in this art.

Fluid for lubricating and cooling purposes may be supplied to the valve 33 by an oil supply pipe 41 extending through a suitable stuffing box 42 and by means of which oil under pressure is constantly supplied to the valve 33. Oil escape passageways or ports 43 are provided as shown, see Fig. 2, through the wall of the valve 33, the pipe sections 29 and the casing 12, whereby oil will be supplied to the oil wells 28 for lubrication of the pipe 26, and, overflowing from said oil wells, will thoroughly lubricate and cool the walls of the cylinders 16 and the lower parts of the engine. If desired, said lubricating fluid may be cooled in accordance with any usual or desired practice, as will readily be understood.

Oil grooves without rings are provided in the periphery of valve 33 and in communication with the oil passageways 43. Additional oil openings 44 are provided in the walls of the valve 33 for lubricating the surface of the valve.

By this arrangement a control valve is provided for the engine which is sufficiently removed therefrom to be substantially uninfluenced by the heat thereof, by which all parts of the engine are thoroughly lubricated, in which the exhaust gases serve to heat the incoming fuel and the incoming fuel serves to cool the exhaust gases.

It is also to be understood that the cylinders

26 are equipped with suitable spark plugs which may be located in the passages 30 or elsewhere, as customary.

Ignition of the fuel charge may be effected by any known or suitable means, preferably by spark plugs located in the passages 30, or elsewhere as customary.

While I have illustrated and described the preferred form and arrangement of parts for carrying the invention into effect this is capable of variation and modification without departing from the spirit of the invention. I therefore do not wish to be limited to the details described but desire to avail myself of such variations and modifications as fall within the scope of the appended claims.

I claim:

1. An internal combustion engine comprising cooperating reciprocating cylinder and reciprocating piston and double throw crank shaft member operatively connected with said cylinder and piston; a stationary combined intake and exhaust pipe passing through the head of said cylinder upon which said cylinder head reciprocates; and valve means for supplying said cylinder with fuel and exhausting it through said pipe.

2. The internal combustion engine described in claim 1, in which the intake and exhaust pipe is provided with separate intake and exhaust branches at its outer end.

3. The internal combustion engine described in claim 1, in which the intake and exhaust pipe is provided with separate intake and exhaust branches at its outer end, and the means of supply and exhaust including a valve casing supported by said pipe branches; and a valve in said valve casing operatively connected for fuel distribution.

4. The internal combustion engine described in claim 1, in which the cylinder is enclosed in a casing having diametrically opposed segmental cylinder guides encompassing and guiding said cylinder in its reciprocation.

VERNON D. BROTT.
